UNITED STATES PATENT OFFICE.

THOMAS ROWE, OF NEW YORK, N. Y.

CLOTHES-DRIER.

SPECIFICATION forming part of Letters Patent No. 257,765, dated May 9, 1882.

Application filed January 31, 1882. (Model.)

To all whom it may concern:

Be it known that I, THOMAS ROWE, a citizen of the United States, resident of New York, in the county of New York and State of New York, have invented a new and valuable Improvement in Clothes-Driers; and I do hereby declare that the following is a full, clear, and exact description of the construction and operation of the same, reference being had to the annexed drawings, making a part of this specification, and to the letters and figures of reference marked thereon.

Figure 1 of the drawings is a representation of a perspective view. Fig. 2 is a section. Fig. 15 3 is a detail.

This invention has relation to clothes-driers; and it consists in the construction and novel arrangement, in connection with the uprights of the frame, of the metallic elliptical spring-bands, embracing two adjacent posts or uprights, and designed to hinge and connect said posts or uprights together, all as hereinafter set forth, and especially pointed out in the claim appended.

25 In the accompanying drawings, the letters *a a* designate the uprights or posts of a clothes-drying frame having the ordinary cross-bars, *b b*. The clothes-drier consists usually of several sectional frames, each of which consists of 30 two uprights, *a*, and connecting cross-bars *b*. In order that these sectional frames may be connected so as to open and close at any desired angle, hinges of various kinds have been employed.

35 The present invention involves the employment of elliptical spring-metal bands *c c*, which embrace the two uprights to be connected, holding them together with a firm and elastic pressure, which closely follows up any wearing or 40 shrinkage of the posts and prevents them from shaking or becoming loose, at the same time allowing the posts to rotate smoothly in the bands during the folding or unfolding of the frames. These spring-band connections are 45 adjusted to the posts with great facility. A moderate pressure on the sides of the band will serve to elongate its greatest diameter suffi-

ciently to freely permit the introduction together of two of the uprights. The pressure having then been withdrawn from the spring, 50 its resilience will cause it to clasp the two uprights firmly and closely, keeping them, as well as the spring-band itself, in proper position.

The metallic bands may be economically constructed of flat spring metal, the ends of the 55 strips being riveted together, or connected in any other ordinary and suitable manner. The bands may be polished or varnished to obviate rusting, and are designed to impart to the drier-frame security and stability, strength and durability.

It will be observed that in folding or unfolding the drier the posts roll upon each other in frictional contact, being compressed against each other by the bands, and that at the same 65 time their bearings at *e e* move with facility against the smooth inner surfaces of the bands, so that there is no reaction after adjustment, the sections of the drier taking their new position at once and holding it by virtue of the 70 frictional pressure between the posts.

I am aware that bands of india-rubber have been used to connect the posts of clothes-driers, and I do not claim such devices.

I am also aware that cast-metal socket-hinges, 75 made in the form of the figure 8, and twisted wire hinges representing two united figures of the same character, have been used in the construction of clothes-driers, none of which are my invention.

80 What I claim, and desire to secure by Letters Patent, is—

In combination with the uprights *a a* of a folding clothes-drier, the elliptical spring-metal bands *c*, embracing said uprights to connect 85 and hinge them together, as specified.

In testimony that I claim the above I have hereunto subscribed my name in the presence of two witnesses.

THOMAS ROWE.
